UNITED STATES PATENT OFFICE

2,549,534

SKI EDGING

Arthur Wright Shultz, Sun Valley, Idaho

Application September 28, 1949, Serial No. 118,436

2 Claims. (Cl. 280—11.13)

1

This invention relates to new and useful improvements and structural refinements in edgings for skis, and the principal object of the invention is to eliminate shearing of screws whereby edgings are secured to a ski, this object being achieved by the provision of means for connecting together end portions of adjacent edgings in such manner that they present, together with the connecting means, a smooth outer surface, devoid of screw heads or other protuberances.

An improvement feature of the invention, therefore, resides in the provision of the connecting means, while another feature lies in the connection which permits the adjacent end portions of the edgings to slide longitudinally with the bending or flexing movement of the ski when in use.

Some of the advantages of the invention reside in its simplicity of construction, in its economical manufacture, and in its adaptability for use on skis of different sizes and types.

With the above more important objects and features in view and such other objects and features as may become apparent as this specification proceeds, the invention consists essentially of the arrangement and construction of parts as illustrated in the accompanying drawings, in which:

Figure 1 is a fragmentary underside plan view of a ski with edgings constructed in accordance with the teachings of the invention;

Figure 2 is a fragmentary cross sectional detail taken substantially on the plane of the line 2—2 in Figure 1;

Figure 3 is a fragmentary cross sectional view, taken substantially on the plane of the line 3—3 in Figure 2; and

Figure 4 is a group perspective view of the components of the invention.

Like characters of reference are employed to designate like parts in the specification and throughout the several views.

Referring now to the accompanying drawings in detail, the general reference character 10 designates a ski provided in bottom longitudinal edge portions thereof with elongated and open-sided channels 12 to accommodate a set of metallic edging strips 14.

The instant invention concerns itself particularly with the provision of means for connecting adjacent end portions of the strips 14, it being understood, of course, that intermediate portions of the strips are secured in the channels 12 by suitable screws 16 in the conventional manner.

The edging strip connecting means consists of an elongated socket 18 which has its base portion 20 secured by a suitable screw 24 in a depression or seat 26 provided in the ski 10 intermediate the ends of the channel 12, it being noted that

2

the socket 18 is provided with a dovetailed slide 28 to slidably receive complementary, dovetailed tongues 30 provided at the adjacent ends of the edging strips 14.

5 It is to be noted that the outer surfaces of the sockets 18, tongues 30 and strips 14 are flush with the bottom surface 32 of the ski, so that no protuberances are present and the use of conventional screws in the end portions of the edging strips is eliminated. Matters are so arranged that the adjacent ends of the tongues 30 in the socket 18 are normally spaced apart as indicated at 34, so that the tongues 30 may slide in the socket 18 in both directions as required by the bending or flexing of the ski when in use.

It is believed that the advantages and use of the invention will be clearly apparent from the foregoing disclosure and accordingly, further description thereof at this point is deemed unnecessary.

While in the foregoing there has been shown and described the preferred embodiment of this invention, it is to be understood that minor changes in the details of construction and arrangement of parts may be resorted to without departing from the spirit and scope of the invention as claimed.

Having described the invention, what is claimed as new is:

30 1. In a ski, the combination of a runner having an elongated open sided channel in a bottom longitudinal edge portion thereof, an elongated dovetailed socket having open ends and secured to the runner intermediate the ends of said channel, a set of edging strips fitted in the channel at opposite ends of said socket, dovetailed tongues provided at adjacent ends of said strips and fitted in opposite end portions of the socket, said tongues being slidable in said socket upon flexing of the runner, and said socket and said tongues having outer surfaces flush with the bottom surface of said runner.

2. The device as defined in claim 1 wherein said runner is provided intermediate the ends of said channel with a depression constituting a seat for said socket.

ARTHUR WRIGHT SHULTZ.
